UNITED STATES PATENT OFFICE

2,197,799

APPARATUS FOR THE TREATMENT OF
HYDROCARBONSLon S. Gregory, Tulsa, Okla., assignor to Phillips
Petroleum Company, a corporation of Delaware

Application October 11, 1937, Serial No. 168,480

1 Claim. (Cl. 196—110)

This invention relates to the treatment of hydrocarbon oils, and more particularly to apparatus for carrying out catalytic treatment of the type in which hydrocarbon oils are contacted with catalysts.

Schulze and Buell in their Patent No. 2,016,271 describe a process for converting sulfur compounds such as mercaptans to hydrogen sulfide by passing hydrocarbon vapors containing organic sulfur impurities over a bauxite catalyst at temperatures of 600—750° F. The hydrogen sulfide is then removed from the vapors.

Miller, Henriksen and Zurich, in their Patent No. 1,895,081 disclose desulfurization and reforming to improve the anti-knock properties of hydrocarbon oils by passing said oils in vapor phase over certain catalysts of the clay type at elevated temperatures of from 600—1500° F.

These catalytic processes are examples of the type process in the practice of which this invention finds its application, although it is to be understood that the invention is generally applicable to the treatment of hydrocarbons at elevated temperatures, with solid catalysts.

An object of this invention is to provide apparatus for carrying out catalytic treating processes.

A further object of the present invention is the provision of apparatus for catalytic treatment of hydrocarbons in which the catalyst may be revivified in situ, when spent, without interruption of the treating operation.

Another object of this invention is the provision of apparatus for the catalytic treatment of petroleum oils which will utilize heat supplied thereto in an economical and efficient manner.

Other objects and advantages of the invention will be apparent during the course of the following description.

In the accompanying drawings, forming a part of this specification, and in which like numerals are employed to designate like parts throughout the same:

Figure 1 is a plan view in section of one form of apparatus embodying the present invention.

Figure 2 is an elevation in section of the apparatus shown in Figure 1.

Figure 3 is a diagrammatic view illustrating the invention as applied in a catalytic treating operation.

Figure 4 is a detached sectional view of one of the reaction tubes employed in the apparatus of the present invention.

Referring to the drawings, wherein there is shown a preferred embodiment of the present

invention, there is illustrated in Figures 1 and 2 end walls and side walls 10 and 11 respectively, which define a furnace 12 suitably enclosed as by a roof supported in any conventional manner. Spaced headers 13 and 14 are interconnected by a plurality of tubes 15 joined to the headers by joints 16, and forming a bank of reaction tubes, generally indicated by the letter A. A similar bank of reaction tubes, generally indicated by the letter B, comprises spaced headers 13' and 14' interconnected by a plurality of reagent tubes 15' joined to the headers by joints 16'. Each of the reagent tube banks is mounted on either side of the central portion of the furnace 12, supported by the furnace walls 10 and 11 and situated at an angle to the horizontal which conveniently may be the angle of repose of the particular catalyst with which the tubes are filled. While it is preferred that the tubes be placed at an angle to the horizontal, the invention is not intended to be limited thereby.

Centrally mounted in the furnace 12, between the reagent tube banks and preferably adjacent thereto, is a group of heater tubes 17 interconnected as by return bends 18 thus forming a heater coil generally indicated at C which is supported in any convenient manner as by the side walls 11.

Baffles 19 are centrally located in the furnace 12 and extend from the floor 20 to a point adjacent each side of the heater coil C thus forming intercommunicating chambers 23, 23' and 23'' in which burners, diagrammatically illustrated, indicated by the numerals 21, 22 and 22', respectively, are located. The furnace 12 is placed in communication with stacks 24 and 24' by flues 25 and 25' in each of the chambers 23' and 23''.

Referring more particularly to Figure 4, there is shown a sectional enlarged view of a portion 40 of a reaction tube; each joint 16, 16' has a screen 26 mounted therein which serves to maintain the catalyst in place in the tubes 15 and 15'. This catalyst may consist of any solid catalyst material employed in processes to which the present invention is applicable. For example, if the apparatus is to be used in a desulfurization process it may comprise any of the catalysts of the clay type, such as fuller's earth, or it may comprise bauxite, or catalyst mounted on solid carriers, which may be inert or may exert catalytic action themselves, all of which will be readily understood by those skilled in the art.

The operation of the apparatus of this invention will best be understood by reference to 55

the flow diagram shown in Figure 3, in which the apparatus of the present invention is diagrammatically shown in place in one type of treating plant.

- 5   Hydrocarbon vapors to be treated are taken from the fractionator 50 through line 51 to clay tower 52, wherein they are subjected to the conventional clay treating process for the removal of unstable color and gum forming constituents.
- 10   Any other conventional treatment may be employed, or none at all if the vapors are comparatively free of gum forming components. From tower 52 the vapors are passed through line 53 to heat exchanger 54 wherein heat is imparted 15 from vapors leaving the treating process. The vapors are now passed through the line 55 and the heater tubes 17 to line 56, which interconnects the reaction tube banks A and B with the heater coil C and is provided with control valves 20 57 and 58 which may be opened and closed to direct the vapors from the heater coil 17 to a selected bank of reaction tubes. Thus, with valve 57 closed and valve 58 open, the vapors will pass through line 56 to header 13, reaction tubes 15, 25 header 14 to line 59 (valves 70 and 69 being closed) and valve 60 to heat exchanger 54 wherein part of their heat is given up to the vapors entering the heat exchanger through line 53. When bank A is operating as the treating unit, 30 valve 60' will of course be closed. From heat exchanger 54, the vapors may be taken out of the system or they may be passed through line 61 to clay towers 62 wherein they may be treated for the removal of any color or gum forming impurities produced during the treating operation and thence out of the system to a cooler and condenser not shown.
- 35   As the catalyst in bank A becomes spent the vapors from the heater coil C will be diverted 40 to bank B by closing valve 58 and opening valve 57, the vapors then passing through header 13', reaction tubes 15', header 14', line 59' and valve 60' (valve 60 being closed) to the heat exchanger 54. During this operation valves 70' and 69' 45 will be closed.

Reagent bank A is now ready for regeneration or reactification, which in the case of catalyst of the clay or bauxite type may be conveniently accomplished by burning with air and steam as will 50 be clearly understood by those skilled in the art. Air and steam will flow through the lines 63 and 64, respectively, to the line 65, where they will be mixed and passed through line 65, valve 66, line 67, to header 13, reaction tubes 15 and header 55 14, line 68 and valve 69 to stack 24. Valves 70 and 60 will be closed during this operation. After regeneration of the spent catalyst, bank A will act as a standby unit until bank B has become spent, whereupon air and steam entering 60 through line 65 will be diverted through line 65' by closing valve 66 and opening valve 66', the air and steam then passing through line 67', header 13', reagent tubes 15', header 14' and line 68' controlled by valve 69' to stack 24'. In this 65 manner, it will be apparent that the treating operation may be carried on continuously with regeneration of the spent catalyst in one bank while treating with the other.

Referring more particularly to Figure 2, the 70 method of heating the heater tubes and/or re-

action tubes, which is a feature of the present invention, may be varied considerably with the burner and tube arrangement shown. With the burners 21 operating and draft taken only from the stack 24, the heater tubes will be heated by 5 convection and radiation, the bank of reaction tubes A by convection, and the other bank B will not be heated. With the burners 21 operating and with draft from both stacks 24 and 24', the heater tubes will be heated by radiation 10 and convection and both banks of reaction tubes will be heated by convection. With the burners 21 and either of the burners 22 or 22' under the reaction tubes operating with draft taken to the stack 24' or 24, respectively, one bank of reaction tubes and the heater tubes will be heated by 15 radiation and convection and the other bank by convection alone, or if the draft is taken from the stack adjacent the burner 22 or 22', which ever is operated, that bank of reaction tubes 20 above that particular burner, and the heater tubes will be heated by both radiant and convection heat while the other reagent bank will not be heated. As a further alternative, all 25 burners may be operated and both stacks used, in which case both reaction banks and the heater tubes will be heated by both radiation and convection. It will be apparent that by this arrangement great variation in the degree of heating of the vapors and reaction tube banks may 30 easily be obtained. This provision adapts the treating apparatus to a wide range of treating conditions which is highly desirable when different catalysts are used and different results desired. For instance, if it is desired merely to 35 convert the organic sulfur compounds to hydrogen sulfide lower temperatures are employed than when continued desulfurization and treatment to increase the anti-knock characteristics of the hydrocarbons being treated is to be accomplished.

It is to be understood that the form of the present invention, herewith shown and described, is to be taken as a preferred embodiment of the same, and that various changes in shape, size 45 and arrangement of parts may be resorted to, without departing from the spirit of the invention, or the scope of the subjoined claim.

Having thus described my invention, I claim:

In an apparatus for catalytic treatment of hydrocarbons in vapor state, the combination comprising a furnace having three compartments, a burner in a first compartment, the other two compartments being connected to the first compartment for transfer of heat by convection, 50 heat exchange means in the first compartment arranged to receive radiant heat from the burner, a pair of headers in each of the other compartments, catalyst tubes connecting the headers, one header in each compartment having connection with one end of the heat exchanger, a valve in the connection, a treated vapor line connected to the other headers, valve means between the other headers and the treated vapor line, steam and air lines connected to one of the 55 headers in each of the other compartments, burn-out lines connected to the other headers, and valve means between the last mentioned lines and the catalyst containers.

LON S. GREGORY. 70
